US00D981161S

(12) **United States Design Patent** (10) **Patent No.:** **US D981,161 S**
(45) **Date of Patent:** **** Mar. 21, 2023**

(54) **PITCHER**

(71) Applicant: **Rubbermaid Incorporated**, Atlanta, GA (US)
(72) Inventors: **Bill Croft**, Huntersville, NC (US); **Tim Haley**, Kalamazoo, MI (US); **Greg Shoemaker**, Cornelius, NC (US); **Jeff Stark**, Davidson, NC (US); **Caleb Teerman**, Grand Rapids, MI (US)

(73) Assignee: **Rubbermaid Incorporated**, Atlanta, GA (US)

(**) Term: **15 Years**

(21) Appl. No.: **29/770,523**

(22) Filed: **Feb. 12, 2021**

(51) LOC (14) Cl. **07-01**

(52) U.S. Cl. **D7/317; D7/622**

CLAIM

The ornamental design for a pitcher, as shown and described.

DESCRIPTION

FIG. 1 is a perspective view of a pitcher showing the new design;

FIG. 2 is a right side elevation view of the pitcher of FIG. 1;

FIG. 3 is a left side elevation view of the pitcher shown in FIG. 1;

FIG. 4 is a front side elevation view of the pitcher shown in FIG. 1;

FIG. 5 is a rear elevation view of the pitcher shown in FIG. 1;

FIG. 6 is a top plan view of the pitcher shown in FIG. 1; and, FIG. 7 is a bottom plan view of the pitcher shown in FIG. 1.

The broken lines in the figures illustrate unclaimed environment and form no part of the claimed design.

1 Claim, 5 Drawing Sheets
